UNITED STATES PATENT OFFICE.

JOSEPH W. LAWSON, OF STERLING, NEBRASKA.

DESIGN FOR A PLOW POINT OR SHARE.

SPECIFICATION forming part of Design No. 14,095, dated July 17, 1883.

Application filed May 17, 1883. Term of patent 14 years.

To all whom it may concern:

Be it known that I, JOSEPH W. LAWSON, of Sterling, in the county of Johnson and State of Nebraska, have invented a new and Improved Design for a Plow Point or Share, of which the following is a full, clear, and exact description.

This invention relates to plow points or shares of a plate form; and it consists in a novel 10 shape and design for such points or shares by forming them to present opposite flat sides, beveled or chamfered off in reverse directions at their opposite ends, and which have convex marginal contours converging toward one 15 another on the shortest of two unequal parallel side margins that determine the width of the plate. The plate is also provided along and near its longest side margin with holes of 20 double and reverse tapering or flaring configuration on opposite sides of it.

Reference is to be had to the accompanying drawings, forming a part of this specification, in which similar letters of reference indicate corresponding parts in both the figures. 25 Figure 1 represents a view in perspective of a plow point or share of plate form, showing my improved design; and Fig. 2 is a longitudinal cross-section taken near the longer side margin of the plate and intersecting the holes 30 thereof.

A is a plate, having opposite flat or straight

sides, *aa*, beveled or chamfered off in reverse directions, as at *b b*, at the opposite ends of the plate. These ends have convex marginal contours, as at *c c*, converging toward one another 35 on the shortest, *d*, of two unequal parallel side margins, *d e*, that determine the width of the plate. The holes *f g* are arranged consecutively along the plate, near the longest side margin, *e*, thereof, and are made to present 40 double and reverse flaring configurations on opposite sides of the plate, as shown in Fig. 2 of the drawings.

Having thus described my invention, I claim as new and desire to secure by Letters Patent— 45

1. A design for a plow point or share, consisting of a form having flat sides made to present convex marginal contours at its opposite ends, and reverse bevels on its opposite sides at said ends, connected by parallel side margins of unequal length, as shown and described. 50

2. A design for plow points or shares having opposite side margins of unequal length, and ends of convex marginal contours, with reverse bevels on opposite sides of the plate, as 55 shown and described.

JOSEPH W. LAWSON.
